ELECTRODE HOLDER

Ellis R. Smith, Bradford, Pa.

Application August 5, 1937, Serial No. 157,628

1 Claim. (Cl. 219—8)

This invention relates to electrode holders and has for an object to provide a holder which may be easily operated in air craft construction, which is compact and can be used in small spaces, and which will be provided with an insulating collar forming a support for the electrode when not in use and which forms means for moving the clamp rod to operative and to released positions when in use.

A further object is to provide a device of this character which will be formed of a few strong simple and durable parts, which will be inexpensive to manufacture and which will not easily get out of order.

With the above and other objects in view the invention consists of certain novel details of construction and combinations of parts hereinafter fully described and claimed, it being understood that various modifications may be resorted to within the scope of the appended claim without departing from the spirit or sacrificing any of the advantages of the invention.

In the accompanying drawing forming part of this specification,

Figure 1 is a longitudinal sectional view of an electrode holder constructed in accordance with the invention.

Figure 2 is a longitudinal sectional view of the electrode holder taken in a plane at right angles to the plane of Figure 1.

Figure 3 is a side elevation of the electrode holder.

Figure 4 is a top plan view of the electrode holder.

Referring now to the drawing in which like characters of reference designate similar parts in the various views, 10 designates a tubular frame one end of which is equipped with a sleeve 11 of insulating material forming a handle. From the handle to the end of the frame a tough high heat resisting insulation 8 is applied to the frame.

The handle is secured in place by screws 12 and below the screws the frame is flattened as shown at 13 and equipped with a screw 14 by means of which the conductor 15 is electrically attached to the tubular frame.

The tubular frame is provided near the handle and on opposite sides thereof with elongated slots 16. A sleeve 17 is slidably mounted upon the tubular frame and is provided with a flange 18 of insulating material. The sleeve is connected to a clamp rod 19 slidably mounted in the tubular frame, by means of a pin 20 which passes through the slots 16 in the tubular frame and through the

clamp rod. The collar 18 constitutes a grip through the medium of which the sleeve may be moved when it is desired to retract the clamp rod to released position. The collar also forms a support for the tool when laid down on the work and prevents shorting.

A fiber disc 21 is arranged within the tubular frame at the flattened end thereof and a helical spring 22 bears with one end upon the disc and with its opposite end upon the clamp rod 19 to urge the clamp rod outwardly to operative position.

The tubular frame is provided with an obliquely disposed slot 23 which receives the welding wire or rod 24. The rod is clamped to the bottom of the slot by the spring pressed clamp rod 19.

In operation the operator may hold the tool in one hand and place his thumb against the collar 18 to retract the clamp rod 19. Thereupon the welding rod may be slid along the tubular frame and passed into the slot 23. Then the collar 18 may be released to permit the clamp rod to be moved to clamping position by the spring 22.

From the above description it is thought that the construction and operation of the invention will be fully understood without further explanation.

What is claimed is:

An electrode holder comprising an insulated tubular frame, a clamp rod slidably mounted in the frame, there being oppositely disposed obliquely extending slots in the end of the tubular frame adjacent to the end of the clamp rod, a tubular handle of insulating material sleeved on the end of the tubular frame opposite the slotted end thereof, the tubular frame being provided near the handle with oppositely disposed longitudinally extending slots, a cylindrical collar of insulating material slidably sleeved upon the tubular frame at said longitudinal slots, a pin connected at the ends to the collar and to the clamp rod and slidably engaged through said longitudinally extending slots, said collar terminating in a flange constituting a grip through the medium of which the collar may be slid toward the handle to retract the clamp rod from the obliquely slotted end of the tubular frame, said flange forming a supporting rest for the electrode holder when it is not in use, and a spring housed in the tubular frame in rear of the clamp rod and urging the clamp rod forwardly into the obliquely slotted end of the tubular frame.
